UNITED STATES PATENT OFFICE

160,970

RADIO RECEIVER CABINET

Carl Reynolds, Jr., Birmingham, Mich., assignor
to Avco Manufacturing Corporation, Cincinnati,
Ohio, a corporation of Delaware

Application August 31, 1949, Serial No. 4,779

Term of patent 14 years

(Cl. D56—4)

To all whom it may concern:

Be it known that I, Carl Reynolds, Jr., a citizen of the United States, residing at Birmingham, Michigan, in the county of Oakland, have invented a new, original, and ornamental Design for a Radio Receiver Cabinet, of which the following is a specification, reference being had to the accompanying drawing, forming a part thereof.

In the drawings:

Fig. 1 is a perspective view of the front, top and side of a radio receiver cabinet showing my new design;

Fig. 2 is a side elevational view; and

Figs. 3 and 4 are cross-sectional views taken, respectively, on lines 3—3 and 4—4 of Fig. 1, looking in the direction of the arrows.

I claim:

The ornamental design for a radio receiver cabinet, as shown.

CARL REYNOLDS, JR.
